of Delaware

Application October 11, 1937, Serial No. 168,321

11 Claims. (Cl. 62—5)

My invention relates to refrigeration, and more particularly to a control device for refrigeration apparatus.

It is an object of my invention to provide an improved control device which is sensitive and reliable in operation for controlling the energy supply of refrigeration apparatus. More particularly, it is an object of my invention to provide an improved control device for controlling the energy supply of refrigeration apparatus whereby a temperature range within which a cooling element is maintained may be widened or diminished at will. I accomplish this by providing a control device whereby a low temperature at which the energy supply to the refrigeration apparatus is reduced or shut off may be raised or lowered at will and independently of a higher temperature at which the energy supply is increased or again instigated after a shut-off period. In addition to widening or diminishing the temperature range within which the cooling element may be maintained, the control device is adjustable whereby the temperature range of the cooling element may be raised or lowered.

Another object of my invention is to provide an improvement in refrigeration apparatus having a main burner and a pilot burner, whereby a valve of a control device for the main burner is also utilized as a safety valve to automatically shut off the supply of fuel to the main burner when the flame of the pilot burner is extinguished. I accomplish this by connecting the pilot burner to a control device for the main burner which is so constructed and arranged that it operates in response to fluid pressure to automatically shut off flow of fuel to the main burner if for any reason the flame of the pilot burner is extinguished.

The novel features which I believe to be characteristic of my invention are set forth with particularity in the claims. The invention, both as to organization and method, together with the above and further objects and advantages thereof, will be better understood as I next describe my improved control in connection with absorption refrigeration apparatus like that described in application Serial No. 107,852 of Albert R. Thomas, filed October 27, 1936.

In the drawings, Fig. 1 diagrammatically illustrates refrigeration apparatus of an absorption type provided with a control device and pilot flame burner embodying my invention;

Fig. 2 is an enlarged vertical sectional view taken on line 2—2 of Fig. 3 to illustrate more clearly the control device shown in Fig. 1;

Fig. 3 is a sectional view taken on line 3—3 of

Fig. 2 with the top cover plate removed and some of the internal parts omitted from the casing;

Figs. 4 and 5 are fragmentary sectional views taken on lines 4—4 and 5—5, respectively, of Fig. 2 to illustrate more clearly parts of the control device;

Fig. 6 is a fragmentary sectional view taken on line 6—6 of Fig. 2;

Figs. 7 and 8 are fragmentary sectional views taken on lines 7—7 and 8—8, respectively, of Fig. 3 to illustrate more clearly the flow of gas in the passages in the control device;

Fig. 9 is a fragmentary sectional view taken on line 9—9 of Fig. 3;

Fig. 10 is an enlarged vertical sectional view of the pilot burner shown in Fig. 1; and

Figs. 11 and 12 are vertical sectional views illustrating modifications of the pilot burner shown in Fig. 10.

Referring to Fig. 1, I have shown a cooling coil 10 arranged in a thermally insulated storage compartment 11. The cooling coil 10 forms part of a secondary cooling system including conduits 12 and 13 and a coil 14. The secondary cooling system contains a fluid, such as brine, for example, which is circulated in the system by a pump 15 driven by an electric motor 16. The coil 14 is arranged in thermal exchange relation with a cooling element 17 of refrigeration apparatus. The refrigerating effect produced in cooling element 17 is utilized to cool fluid in coil 14 which flows to cooling coil 10 to produce cold in storage compartment 11.

The cooling element 17 forms part of absorption refrigeration apparatus of a uniform pressure type and like that described in the above application of Albert R. Thomas. In such apparatus a refrigerant is introduced into the cooling element 17 through a conduit 18. In cooling element 17 the refrigerant, such as ammonia, evaporates and diffuses into an inert gas, such as hydrogen, to produce a refrigerating effect to cool fluid in coil 14. The resulting gas mixture of inert gas and refrigerant flows from the lower part of cooling element 17 through conduit 19, outer passage of a gas heat exchanger 20, and conduit 21 into an absorber 22.

In absorber 22 refrigerant gas is absorbed by a suitable liquid absorbent, such as water, which enters through conduit 23. The inert gas, which is practically insoluble and weak in refrigerant, is returned to cooling element 17 through conduit 24, a plurality of tubes forming the inner passage of gas heat exchanger 20, and conduit 25; and

the enriched absorption liquid is conducted from absorber 22 through the outer passage of the liquid heat exchanger 26, vessel 27, conduit 28, generator 29, and conduit 30 to a coil 31.

5 The coil 31 is heated by a burner 32 whereby liquid is raised by vapor-lift action through conduit 33 into a vessel 34 in which refrigerant vapor and absorption liquid are separated. Liberated refrigerant vapor flows downward through conduit 35 into generator 29. This vapor, together with refrigerant vapor expelled out of solution in generator 29 due to heating thereof by burner 32, flows through conduit 28 into vessel 27. From vessel 27 refrigerant vapor flows upward through conduit 36 and a liquid cooled rectifier 37 into a condenser 38 in which the refrigerant is liquefied. The liquefied refrigerant flows from condenser 38 through conduits 39 and 40 into rectifier 37, whereby any absorption liquid vapor accompanying the refrigerant vapor is condensed and drains back through conduit 36 into vessel 27. From rectifier 37 liquid refrigerant is returned to cooling element 17 through conduit 41, coil 42, and conduit 18 to complete the refrigerating cycle. In coil 42 liquid refrigerant is pre-cooled by evaporation thereof into enriched gas which flows from and to the gas heat exchanger 20 through conduits 43 and 44.

30 The weakened absorption liquid from which refrigerant has separated flows from vessel 34 through conduit 45, the inner passage of liquid heat exchanger 26, and conduit 23 into the upper part of absorber 22. The heat liberated with absorption of refrigerant vapor in absorber 22 is 35 transferred to a cooling medium which flows upward through a coil 46. The coil 46 may be connected to a conduit 47 which extends through condenser 38 whereby the latter is cooled by the same cooling medium as the absorber 22.

40 A vessel 48 having an opening 49 in the bottom thereof is arranged in absorber 22. The upper part of vessel 48 is connected by a conduit 50 to the upper part of conduit 40, so that any inert gas which may pass into condenser 38 can flow into 45 the gas circuit. Any refrigerant vapor not liquefied in condenser 38 flows through conduit 50 to displace gas in vessel 48 and force such gas into the gas circuit through opening 49, thereby increasing the total pressure in the system. With 50 such increase in pressure in the system, an adequate condensing pressure is obtained to insure condensation of refrigerant vapor in condenser 38.

55 In accordance with my invention the flow of gas to burner 32 is controlled by a control device 51. The control device 51 embodies the control mechanism for refrigeration apparatus which is described in my application Serial No. 113,152, filed November 28, 1936. Referring to Figs. 1 and 60 2, the control device 51 comprises a casing 52 having inlet and outlet openings 53 and 54 to which are connected conduits 55 and 56, respectively. The casing 52 is formed with a partition 57 having an opening within which is fixed a 65 short cylindrical sleeve 58. The sleeve 58 is provided with a central hub 59 which is connected to the sleeve by spaced radial arms 60. The lower and upper ends of sleeve 58 serve as seats for valves 61 and 62 which are disposed in chambers 70 63 and 64, respectively, formed on opposite sides of the partition 57. The valves 61 and 62 are formed of any suitable material, such as artificial rubber commercially known as "Du Prene" or "Thiokol," for example, which is not affected by 75 contact with gas.

The valve 61 may be termed a high temperature safety valve and controls the flow of gas to the burner 32 in response to a thermal element arranged at the lower end of the casing 52. This thermal element comprises a resilient diaphragm 65 and a plate 66 which are secured between the lower end of casing 52 and a cover plate 67. To the plate 66 at an opening therein is secured one end of a tube 68 which extends through an opening in the cover plate 67 and is connected at its other end to a thermal bulb 69. The bulb 69 is arranged in thermal contact with the liquid cooled rectifier 37, as shown in Fig. 1.

10 The resilient diaphragm 65 and plate 66, tube 68, and bulb 69 are charged with a suitable volatile fluid and constitute an expansible fluid thermostat. The resilient diaphragm 65 is adapted to bear against the lower end of a C-shaped spring 70 which is secured at its upper end to the valve 61. A spiral spring 71 is retained in position between the hub 59 and valve 61 to urge the latter to its normally open position.

15 The resilient diaphragm 65 and plate 66, tube 68, and bulb 69 are charged with a suitable volatile fluid and constitute an expansible fluid thermostat. The resilient diaphragm 65 is adapted to bear against the lower end of a C-shaped spring 70 which is secured at its upper end to the valve 61. A spiral spring 71 is retained in position between the hub 59 and valve 61 to urge the latter to its normally open position.

20 If for any reason the temperature of the liquid cooled rectifier 37 becomes relatively high, due to failure of the cooling medium to circulate through the condenser 36, for example, the expansible fluid thermostat becomes effective to urge the valve 61 to its closed position against the tension of spiral spring 71. With the high temperature safety valve 61 moved to its closed position, the supply of gas to burner 32 is shut off completely, whereby heat is no longer applied to the refrigeration apparatus.

25 The main valve 62 is directly connected or mounted on a diaphragm 72 which, with the partition 57, defines the chamber 64 communicating with the outlet 54. The valve 62 and diaphragm 72 are loaded or weighted by metal plates 73 fixed to both sides of the diaphragm. As will be described hereinafter, the valve 62 controls the flow of gas to the burner 32 in response to a 30 thermal element 74 which is located in a chamber 75 formed above the diaphragm 72.

35 In order to maintain a pilot flame for the burner 32 when either of the valves 61 or 62 is closed, I provide a small burner 76 to which gas is conducted through a conduit 77 connected to a by-pass formed in the casing 52. As shown in Figs. 3, 7, and 8, gas flows from chamber 63 through a by-pass including an inclined passage 50 78, a horizontal passage 79, and a vertical passage 80 to the lower end of which is connected conduit 77. The quantity of gas flowing through the by-pass from chamber 63 to the small burner 76 is controlled by a plug valve 81 in horizontal passage 79. The plug valve 81 is provided with a threaded screw head 82 which is movable in a slightly larger passage 83 formed in a boss 84 at the exterior of casing 52. By turning screw 82 from the exterior of casing 52 after removing an outer screw 85, the plug valve 81 can be positioned in passage 79 to regulate the flow of gas to the small burner 76. A coil spring 86 is provided in horizontal passage 79 to permit accurate adjustment of plug valve 81 and prevent undesirable movement thereof.

45 The thermal element 74 is in the form of an expansible diaphragm and is secured to and in communication with a hollow hub member 87. To the hub member 87 is connected one end of a tube 88 which extends through an opening in a cover plate 89 and is connected to a thermal bulb 90. The bulb 90 is arranged in thermal contact with conduit 13 of the secondary cooling system of the refrigeration apparatus, as shown 55 70 75 75

in Fig. 1. The hub member 87 is fixed to a resilient diaphragm 91 which is secured between the upper end of casing 52 and cover plate 89. The cover plate 89 is provided with a temperature adjustment knob 92 for adjusting the position of resilient diaphragm 91 and hence the operating position of thermal element 74. The knob or control member 92 is provided with a pointer 92' which moves about a dial or scale 10 89' which may be formed on cover plate 89.

The thermal element 74, tube 88, and bulb 90 are also charged with a suitable volatile fluid and constitute an expansible fluid thermostat. The thermal element 74 expands and contracts with 15 an increase and decrease of temperature, respectively, and these movements are transmitted to bleeder valves 93 and 94 to effect control of main valve 62. The inlet valve 93 cooperates with the upper end of a passage 95 having the lower 20 end thereof communicating with chamber 63 near the inlet 53. The passage 95 permits the flow of gas from inlet 53 into chamber 75, and, in order to transmit the velocity pressure of the gas stream in this passage, a conical-shaped ring 25 96 is inserted in chamber 63, as shown in Fig. 2.

The inlet valve 93 is guided and urged to its open position by a small spiral spring 97 which is located in the vertical portion of passage 95 formed in an inward extending part 98 of casing 30 52. The outlet valve 94 cooperates with the upper end of passage 80, as shown most clearly in Fig. 7, and permits gas to flow from chamber 75 through conduit 77 to the small burner 76. The outlet bleeder valve 94 is guided and urged 35 to its open position by a small spiral spring 99 which is located in the vertical portion of passage 80 formed in the upper inward extending part 100 of casing 52.

To insure a close fit of bleeder valves 93 and 40 94, the upper ends of passages 95 and 80 are enlarged to receive valve inserts 101 and 102, as shown most clearly in Figs. 4 and 5. The valve inserts 101 and 102 are ring-shaped and project above and below the surfaces of parts 98 and 45 100, respectively, of the casing 52. Valve retaining members 103 and 104 are secured to the parts 98 and 100 to limit the extent to which bleeder valves 93 and 94 can be opened.

The structure in chamber 75 for transmitting 50 movements of thermal element 74 to bleeder valves 93 and 94 includes a lever 105 having a knob or protuberance 106 which bears against thermal element 74. As shown in Fig. 3, the lever 105 is relatively wide and provided with 55 narrow reduced ends. The right hand end of lever 105 is adapted to bear against inlet valve 93, and the left-hand end is provided with an opening in alignment with outlet valve 94. To the underside of lever 105 is secured a flat spring 60 107 having an abutment 108 fixed thereto which extends through the opening in lever 105 and is adapted to bear against outlet valve 94.

The lever 105 is provided with downward extending sides 109 which are pivotally connected 65 to a pin 110 fixed to the sides or tabs 111 formed on the outer end of a flat main spring 112. The inner end of main spring 112 is located about the part 98 of casing 52 and provided with spaced arms 113 which are secured to the underside of 70 part 98, as shown in Figs. 3 and 5.

A differential adjustment screw 114 is located in a hollow vertical boss 115 formed at the upper part of casing 52. The lower threaded portion of screw 114 extends through a threaded opening 75 in the inward extending part 100 of the cas-

ing and is adapted to contact the extreme left-hand end of lever 105. The upper unthreaded portion of screw 114 is enlarged and fits snugly in vertical passage 116 formed in the boss 115. A packing 117 is provided in passage 116 about 5 the unthreaded reduced portion of screw 114. The packing 117 is retained in position by a washer 118 against which bears the upper end of a coil spring 119 located in passage 116. The coil spring 119 compresses the packing 117 to 10 effectively seal the passage 116 and also prevents undesirable axial movement of adjustment screw 114, whereby the latter may be accurately adjusted.

To the upper enlarged end of adjustment screw 15 114 is secured a control knob 120 having a plurality of notches 121 formed about the periphery thereof, as shown most clearly in Fig. 6. A spring 122 secured to the upper part of casing 20 52 is formed with a vertically extending curved portion which is adapted to engage the notches 121 and frictionally hold the knob 120 to the position to which it is adjusted. The control knob 120 is provided with a stop 123 to limit the turning movement thereof to one revolution. 25

The structure located in the upper chamber 75 and just described is capable of operating the bleeder valves 93 and 94 and hence control the valve 62 and flow of gas to burner 32, whereby the cooling element 17 of the refrigeration apparatus will be capable of maintaining storage compartment 11 in a desired low temperature range. The pin 110 exerts an upward force on lever 105 which is derived from main spring 112. If the point at which knob 106 contacts thermal 30 element 74 for the moment is considered the pivoting point of lever 105, the upward force exerted by pin 110 will urge the left-hand end of lever 105 upward and the right hand end downward to move bleeder valves 93 and 94 35 toward their closed positions. The flat spring 107 to which the abutment 108 is fixed is sufficiently strong to overcome the spiral spring 99 and effect closing of outlet valve 94 without deviating from its position shown in Fig. 2. The 40 main spring 112 is sufficiently strong to overcome the combined moments of flat spring 107 and spiral spring 97, and also provide the closing force for inlet valve 93. 45

The operation of the control device is substantially as follows: Let us assume that main valve 62 is in its closed position and that the supply of gas to burner 32 is shut off. Under these conditions inlet bleeder valve 93 is open and outlet bleeder valve 94 is closed. When the temperature of storage compartment 11, and hence the temperature of cooling fluid in conduit 13, tends to rise above a predetermined temperature, the thermal element 74 expands a definite amount. With such expansion of thermal element 74, the 50 lever 105 pivots about the region which bears against the inlet valve 93, whereby the left-hand end thereof moves downward. The spiral spring 99 cooperating with outlet valve 94 urges the latter to move to its open position when the left-hand end of lever 105 moves downward. With inlet valve 93 closed and outlet valve 94 opened, chamber 75 is in communication with passage 80 to which is connected the delivery conduit 77 55 of small pilot flame burner 76. Since the gas flowing into vertical passage 80 from chamber 63 is adjusted to a low pressure by plug valve 81, the pressure in chamber 75 will become relatively 60 low and slightly above atmospheric pressure. 70

While the pressure in chamber 75 is relatively low, the pressure in chamber 63 is that of the gas pressure in supply conduit 55. The plates 73 fixed to diaphragm 72 are of such size that the 5 combined weight of the plates, diaphragm, and main valve 62 will exert a downward force which is less than the force exerted on the underside of valve 62 by gas under pressure in sleeve 58. Since the downward force on diaphragm 72 is 10 less than the force exerted by gas in chamber 63 on the underside of the diaphragm at the relatively small portion covering the sleeve 58, main valve 62 will move upward from its seated position shown in Fig. 2. When main valve 62 cracks 15 open, the gas pressure starts building up in chamber 64, whereby an upward force is exerted on the entire underside of the diaphragm 72 and main valve 62 will remain in its full open position.

The gas now flows to main burner 32 and is 20 ignited by the pilot flame produced by small burner 76, and heat is applied to the refrigeration apparatus whereby refrigeration is produced by cooling element 17. The cooling fluid circulating in the secondary cooling system immediately 25 becomes effective to increase the refrigeration produced in storage compartment 11.

When the temperature of storage compartment 11, and hence the temperature of cooling fluid in conduit 13, tends to fall below a predetermined 30 low temperature, the thermal element 74 contracts a definite amount. With such contraction of thermal element 74, the left-hand end of lever 105 moves upward whereby abutment 108 closes bleeder valve 94, due to the fact that flat spring 35 107 is stronger than spiral spring 99. When thermal element 74 first contracts, inlet bleeder valve 93 remains in its closed position due to the action of main spring 112. With further contraction of thermal element 74 and when the extreme left-hand end of lever 105 contacts adjustment screw 40 114, bleeder valve 94 remains in its closed position even with continued upward movement of lever 105, due to the provision of flat spring 107. Under such conditions the flat spring 107 is bent 45 and flexes away from the underside of lever 105. When lever 105 contacts the adjustment screw 114 and further contraction of thermal element 74 takes place, the lever pivots about its left-hand end whereby the right hand end moves upward 50 and permits spiral spring 97 to move inlet bleeder valve 93 to its open position.

With inlet valve 93 open and outlet valve 94 closed, gas flows through passage 95 from lower chamber 64 or inlet 53 into the upper chamber 55 75. When the gas pressure in chambers 75 and 64 are substantially equal, the diaphragm 72 and main valve 62 will move downward due to the fact that the diaphragm is loaded by the plates 73. The valve 62 will effectively remain in its closed 60 position when it is seated at the upper end of sleeve 58, because the gas under pressure in chamber 75 exerts a downward force over the entire area of diaphragm 72 while the gas under pressure in chamber 63 and sleeve 58 only exerts 65 an upward force on the portion of the diaphragm covering the upper end of sleeve 58.

With the valve 62 in its closed position, heat is no longer applied to the refrigeration apparatus and the refrigerating effect produced by 70 cooling element 17 is reduced. When the storage compartment 11 tends to rise above the predetermined temperature, the thermal element 74 will again expand sufficiently to close inlet valve 93 and open outlet valve 94, as described above. When this occurs the pressure in upper chamber

75 is relieved and the gas from this chamber flows through vertical passage 80 and conduit 77 to small burner 76, whereby the size of the pilot flame is momentarily increased. This coincides with the opening of main valve 62 and insures reliable operation of the small burner 76. The amount of gas discharged from chamber 75 each time main valve 62 opens is equal to the volume of gas contained in this chamber.

In view of the foregoing, it will now be understood that control device 51 operates with a temperature differential and that thermal element 74 is operative to cause main valve 62 to close at a low temperature and to open at a higher temperature. By moving temperature adjustment 15 knob 92 on cover plate 89, the operating position of thermal element 74 may be moved to raise or lower the temperature range in which main valve 62 is opened and closed. The temperature range in which the control device operates may be so 20 adjusted that during the periods when no heat is supplied to the refrigeration apparatus, the cooling element 17 can rise above the freezing temperature, so that defrosting of the cooling element will occur.

The differential adjustment screw 114, which will hereinafter be referred to as an adjustment screw, provides for independent adjustment of the temperature at which the supply of heat to the refrigeration apparatus is shut off. Thus, 30 after the temperature control knob 92 is adjusted to determine the higher temperature at which heat is again delivered to burner 32 after a shut-off period, the adjustment screw 114 can be moved to increase or decrease the temperature 35 differential and vary at will the low temperature at which the supply of heat is shut off. When the adjustment screw 114 is raised or moved upward, more contraction of thermal element 74 is necessary to close outlet valve 94 and open inlet 40 valve 93 to effect closing of main valve 62. The amount of contraction of thermal element 74 that is required to effect closing of main valve 62, of course, determines the low temperature at 45 which the supply of heat to the refrigeration apparatus is shut off.

The control device 51 may be operated manually, if desired, to start heating of the refrigeration apparatus when main valve 62 is closed. This may be accomplished by moving adjustment 50 screw 114 downward so that the latter presses the left-hand end of lever 105 but a slight amount to barely open outlet valve 94. This relieves the gas pressure in upper chamber 75 and permits main valve 62 to open, as described above. When 55 the storage compartment 11 tends to fall below the predetermined low temperature and thermal element 74 has contracted sufficiently, lever 105 will pivot about adjustment screw 114 to close outlet valve 94 and open inlet valve 93, whereby 60 main valve 62 is caused to move to its closed position.

The manual operation just described is very sensitive and the movement of adjustment screw 114 is very critical. If adjustment screw 114 is 65 moved downward too far, the outlet valve 94 will remain open after the right hand end of lever 105 has moved upward to permit the inlet valve 93 to open. With both bleeder valves 93 and 94 open, gas flows through chamber 75 to the small 70 burner 76. This condition is easily recognized by a flaring of the pilot flame produced by small burner 76. I make use of this critical condition to initially adjust the position of adjustment screw 114.

This may be accomplished by turning temperature adjustment knob 92 back and forth while bulb 90 is at a definite temperature, such as room temperature, for example, until thermal element 14 is at such a position that inlet valve 93 is closed and outlet valve 94 is open, whereby main valve 62 is caused to open. The position of pointer 92' on scale 89' is noted and control knob 92 is moved to raise thermal element 14, so that inlet valve 93 opens and outlet valve 94 closes. The pointer 92' of control knob 92 is then returned to a position on scale 89' which is close to the position previously noted. In this position of the pointer 92' both bleeder valves 93 and 94 are closed, and only a small movement of control knob 92 would be necessary to move thermal element 14 downward to open outlet valve 94. With the pointer 92' of knob 92 in this position, the adjustment screw 114 is moved downward sufficiently to press down on the left-hand end of lever 105 to open outlet valve 94. This will be indicated by an increase of the size of the pilot flame produced by small burner 76. With outlet valve 94 open and inlet valve 93 closed, the main valve 62 will move to its open position. The screw 114 may then be moved upward a small distance from this critical condition and knob 120 secured to screw 114, so that stop 123 is in such a position that adjustment screw 114 cannot be moved downward beyond the position to which it has been adjusted. When adjustment screw 114 is raised from this adjusted position, the temperature at which thermal element 14 becomes effective to cause main valve 62 to close is lowered, whereby the temperature differential is increased. The lower shut-off temperature may be varied at will, therefore, and independently of the higher temperature at which main valve 62 is caused to open and again supply heat to the refrigeration apparatus. After temperature adjustment knob 92 is moved to a definite position, the higher temperature at which main valve 62 opens remains substantially the same irrespective of any adjustment of screw 114 to vary the lower temperature at which valve 62 closes.

In accordance with my invention the small burner 76 is constructed and arranged so that main valve 62 of control device 51 is utilized as a safety valve, if for any reason the pilot flame is extinguished. As shown in Fig. 10, the small burner 76 includes a valve body comprising a part 124 threadedly secured to a part 125. The part 125 is provided with an inlet opening to which is connected the outer end of conduit 77. The part 124 is formed with a valve seat which cooperates with a valve 126. The valve 126 is connected to a valve stem 127 which extends through an opening in part 124 and is secured to a snap-acting thermostatic diaphragm 128 which is secured between the open end of a diaphragm housing 129 and a curved outer metallic disc 130.

A passage 131 formed in part 124 communicates with an inclined passage 132 formed in part 125. At the outer end of passage 132 is secured a nozzle 133 to provide a jet pilot flame for main burner 32. A heat conductor 134 is secured to housing 129 and provided with an extension which is adapted to be heated by the pilot flame. When the burner 76 is lighted, heat is conducted by heat conductor 134 to the thermostatic diaphragm 128.

The small burner 76 is located adjacent to main burner 32 so that the pilot flame produced at

nozzle 133 will be effective to ignite the gas delivered to burner 32. The burner 76 is provided with a small hood 135 which surrounds the nozzle 133 and heat conductor 134, so that the likelihood of the pilot flame being extinguished by sudden air draft is avoided.

The pilot burner 76 is provided with a lighter tube 136 which terminates in the vicinity of disk 130 and heat conductor 134. As shown in Fig. 1, lighter tube 136 is connected to a part 137 secured to the lower part of casing 52. Combustible gas is delivered from inlet 53 through a by-pass in casing 52 to lighter tube 136. As shown in Fig. 9, the lighter tube 136 is connected to the lower end of a vertical passage 138 which terminates in a small chamber 139. The small chamber 139 in turn communicates with a passage 140 which communicates with the inlet 53. Within chamber 139 is located a valve 141 having a stem 142 which is secured to a push-button 143 operable from the exterior of part 137. The push-button 143 is normally urged outward by a helical spring 144 whereby valve 141 remains in its closed position.

When it is desired to provide a flame at the outer end of lighter tube 136 to start pilot burner 76, push-button 143 is pressed inward whereby valve 141 is opened and combustible gas is delivered to the outer end of lighter tube 136. A small screw 145 extending into passage 138 is provided to adjust the size of a lighter tube flame. The lighter tube flame is applied to disk 130 and heat conductor 134, and the heat is conducted to thermostatic diaphragm 128. When diaphragm 128 is heated sufficiently it snaps toward the right to open valve 126 and permit flow of combustible gas from conduit 77 to nozzle 133. The gas discharged from nozzle 133 is ignited by the lighter tube flame to provide the pilot flame.

By providing valve 126 in conduit 77, the main valve 62 is urged to its closed position or remains in its closed position if for any reason the jet pilot flame is extinguished. Normally the pressure in conduit 77 is relatively low so that the gas pressure in upper chamber 75 is effectively relieved when inlet bleeder valve 93 closes and outlet bleeder valve 94 opens. This causes main valve 62 to open and permits gas to be delivered to burner 32 to start a heating period. If the jet pilot flame is extinguished, heat is no longer delivered by heat conductor 134 to diaphragm 128 and the latter cools and snaps toward the left to close valve 126. If the main valve 62 should be closed when this occurs and the thermal element 14 subsequently expands to close inlet bleeder valve 93 and open outlet bleeder valve 94, the gas pressure in upper chamber 75 cannot be relieved. Since gas continues to flow through the by-pass from chamber 63 into passage 80 and conduit 77, the pressure in conduit 77 increases due to the fact that valve 126 is closed. Although outlet bleeder valve 94 is open, therefore, the gas pressure in upper chamber 75 is not relieved and main valve 62 will remain in its closed position, thereby acting as a safety valve.

The same result occurs when main valve 62 is open and the gas pressure in upper chamber 75 is relatively low. If the pilot flame is extinguished under these conditions, the closing of valve 126 causes the pilot gas to back up through passage 80 into upper chamber 75. The gas pressure in chamber 75 fills up due to the flow of gas through the by-pass, and, when the gas pressures in chambers 75 and 64 are substan- 75

tially equal, the main valve 62 moves to its closed position to shut off the flow of gas to main burner 32.

In Fig. 10 I have shown a modification of the 5 pilot burner 16 just described and illustrated in Fig. 10. The pilot burner 76a in Fig. 11 includes a valve body 125a having a passage 131a to which is connected the conduit 77. The flow of gas through passage 131a is controlled by a valve 10 126a which is fixed to snap-acting thermostatic diaphragm 128a secured between the open end of a diaphragm housing 129a and a curved disk 130a. The diaphragm 128a and disk 130a are provided with openings 146 and 147, respectively, 15 with the pilot flame being produced at the regions of openings 147. A sleeve 134a is secured to housing 129a to protect the burner flame as well as assist disk 130a in conducting heat to diaphragm 128a. The lighter tube 136 terminates in the vicinity of housing 129a to heat diaphragm 128a and start operation of burner 76a.

When the pilot flame is burning diaphragm 128a is flexed toward the left and valve 126a is open. If for any reason the pilot flame is extinguished the diaphragm 128a snaps toward the right to close valve 126a. This prevents gas from being relieved from upper chamber 75 of control device 51, as described above, whereby main valve 62 is urged to its closed position to 20 shut off the flow of gas to generator burner 32.

In Fig. 12 I have diagrammatically shown a further modification of a pilot burner which does not require a lighter tube to start the operation 25 of the burner. The burner 76b in Fig. 12 includes a U-shaped bracket 148 which is secured in any suitable manner to main burner 32. To the left-hand end of bracket 148 is secured a plunger 149 having a conical-shaped end 150 which serves as a valve. A sleeve 151 connected to conduit 77 extends through an opening in the right-hand arm of bracket 148 and is arranged to slide on plunger 149. The burner flame is maintained at a plurality of openings 152 formed in the enlarged portion of sleeve 151, and the shoulder 153 formed 30 in the sleeve serves as a seat for valve 150. An inverted U-shaped bi-metallic strip 154 is secured to bracket 148 and the left-hand end thereof is adapted to engage the end of sleeve 151. A spring 155 is provided about a reduced portion of sleeve 35 151 to urge the latter toward the left when the strip 154 moves upward to release the left-hand end of sleeve 151.

During operation of burner 76b the parts of the burner are in the position shown in Fig. 12, with 40 the pilot flame heating the bi-metallic strip 154. If for any reason the burner flame is extinguished, the strip 154 is cooled and flexes upward whereby spring 155 becomes effective to move sleeve 151 toward the left. This moves shoulder 153 45 against valve 150 to shut off the flow of gas to the burner, and, as described above in connection with Fig. 10, the main valve 62 is urged to its closed position.

When it is desired to re-light burner 76b conduit 77 is pulled outward or toward the right so that shoulder 153 is moved away from valve 150. After the gas is ignited at the openings 152, conduit 77 is held for an interval of time sufficient 50 for bi-metallic strip 154 to become heated. When strip 154 is heated sufficiently it flexes downward and engages the left-hand end of sleeve 151, whereby conduit 77 may be released.

Although I have shown my improved control 55 device in connection with a particular type of re-

frigeration apparatus, I do not wish to be limited to the particular arrangement set forth. It will be obvious to those skilled in the art that various changes and modifications may be made without departing from the spirit and scope of 5 the invention. I therefore aim in the following claims to cover all such modifications and changes as fall within the true spirit and scope of the invention.

What is claimed is:

1. In absorption refrigeration apparatus including a cooling element, a generator, and a burner for heating said generator, a control device including a diaphragm operated valve to control flow of gas to the burner, structure to permit said gas to exert force on both sides of said diaphragm, mechanism to effect operation of said valve and including an element responsive to temperature or pressure to control the gas capable of exerting force on one side of said diaphragm, means to bodily move said element to regulate the operation of said valve, and means independent of bodily movement of said element to further regulate the operation of said valve. 20

2. In an absorption refrigeration apparatus including a cooling element, a generator, and a gas burner for heating said generator, a control device including a gas pressure operated valve for controlling flow of gas to said burner, means including a thermostat element and valve means 30 mechanically connected to said element to vary said gas pressure to effect operation of said valve to maintain said cooling element in a temperature range, said valve means including a chamber having gas inlet and outlet valve members, said mechanical connection being such that said valve members are caused to operate in alternation upon movement in either direction of said thermostat element, and means to increase or decrease said temperature range, said last-mentioned means determining the position of said thermostat element at which said outlet valve member closes. 35

3. In absorption refrigeration apparatus having a cooling element, a generator, and a burner for heating the generator, a control device comprising structure including a diaphragm operated valve to control flow of fuel to the burner, said structure being so constructed and arranged that both sides of said diaphragm may be subjected 40 to pressure of fuel, mechanism including an element responsive to temperature or pressure to control the fuel pressure on one side of said diaphragm and thereby effect operation of said valve in a temperature or pressure range to shut off flow of fuel at a low temperature or pressure value and instigate flow of fuel at a higher temperature or pressure value, means to adjust said mechanism to raise or lower the temperature or 45 pressure range in which said valve is operated, and additional means independent of said last-mentioned means and including a part cooperating with said mechanism to increase or decrease said low temperature or pressure value at which 50 flow of fuel is shut off without affecting the higher temperature or pressure value at which flow of fuel is instigated. 55

4. In absorption refrigeration apparatus having a cooling element, a generator, and a burner 70 for heating the generator, a control device comprising structure including a diaphragm operated valve to control flow of fuel to the burner, said structure being so constructed and arranged that both sides of said diaphragm may be sub- 75

jected to pressure of fuel, mechanism including an element responsive to temperature or pressure to control the fuel pressure on one side of said diaphragm and thereby effect operation of said valve in a temperature or pressure range to shut off flow of fluid at a low temperature or pressure and instigate flow of fuel at a higher temperature or pressure, means including a first movable member to adjust said mechanism to raise or lower the temperature or pressure range in which said valve is operated, and means including a second movable member associated with said mechanism to widen or diminish said temperature or pressure range in which said valve is operated independent of and in addition to the regulation effected by said last-mentioned means.

5. In absorption refrigeration apparatus having a cooling element, a generator, and a burner for heating the generator, a control device comprising structure including a casing having an inlet and outlet, and a diaphragm operated valve in said casing for controlling flow of fuel between the inlet and outlet, said structure being so constructed and arranged that both sides of said diaphragm may be subjected to pressure of fuel, mechanism within said casing including an element responsive to temperature or pressure and a part actuated by such element to control the fuel pressure on one side of said diaphragm and thereby effect operation of said valve, means operable from the exterior of said casing to adjust said mechanism to regulate the operation of said valve, and means including a member associated with said part and operable from the exterior of said casing to further regulate the operation of said valve independent of and in addition to the regulation effected by said last-mentioned means.

6. In absorption refrigeration apparatus having a cooling element, a generator, and a burner for heating the generator, a control device comprising structure including a diaphragm operated valve to control flow of fuel to the burner, said structure being so constructed and arranged that both sides of said diaphragm may be subjected to pressure of fuel, mechanism including an element responsive to temperature or pressure to control the fuel pressure on one side of said diaphragm and thereby effect operation of said valve in a temperature or pressure range between a low and higher value to shut off and instigate flow of fuel, means to bodily move said element to raise or lower said temperature or pressure range in which said valve is operated, and means independent of said last-mentioned means and including a part cooperating with said mechanism to increase or decrease one of the temperature or pressure values without affecting the other temperature or pressure value in the temperature or pressure range in which said valve is operated.

7. In absorption refrigeration apparatus having a cooling element, a generator, and a burner for heating the generator, a control device comprising structure including a diaphragm operated valve to control flow of gas to the burner, said structure being so constructed and arranged that both sides of said diaphragm may be subjected to pressure of fuel, an element responsive to temperature or pressure, mechanism associated with said element to effect operation of said valve in a temperature or pressure range, means to bodily move said element to raise or lower

said temperature or pressure range in which said valve is operated, and means including an adjustable part associated with said mechanism to widen or diminish the temperature or pressure range in which said valve is operated without bodily moving said element. 5

8. In absorption refrigeration apparatus having a cooling element, a generator, and a burner for heating the generator, a control device comprising structure including a casing having an inlet and outlet for fuel, a diaphragm operated main valve within said casing to control flow of fuel between the inlet and the outlet, said structure being so constructed and arranged that both sides of said diaphragm may be subjected to pressure of fuel, mechanism to control the fuel pressure on one side of said diaphragm and thereby effect operation of said main valve, such mechanism including an expansible and contractible element within said casing and auxiliary valve means actuated by expansion and contraction of said element, means to bodily move said element to regulate the operation of said main valve, and means including a part associated with said mechanism to further regulate the operation of said main valve without bodily moving said expansible and contractible element. 10 15 20 25

9. In absorption refrigeration apparatus having a cooling element, a generator, and a burner for heating the generator, a control device comprising structure including a diaphragm operated main valve to control flow of fuel to the burner, said structure being so constructed and arranged that both sides of said diaphragm may be subjected to pressure of fuel, mechanism including an element responsive to temperature or pressure and auxiliary valve means actuated by said element to control the fuel pressure on one side of said diaphragm and thereby effect operation of said main valve, means to bodily move said element to regulate the operation of said main valve, and additional means including a part associated with said mechanism to further regulate the operation of said main valve without bodily moving said element. 30 35 40 45

10. In absorption refrigeration apparatus having a cooling element, a generator, and a burner for heating generator, a control device comprising structure including a diaphragm operated main valve to control flow of fuel to the burner, said structure being so constructed and arranged that both sides of said diaphragm may be subjected to pressure of fuel, mechanism to control the fuel pressure on one side of said diaphragm and thereby effect operation of said main valve, said mechanism including an element responsive to temperature or pressure, auxiliary valve means, and a part operatively associating said element and said auxiliary valve means, means to adjust said mechanism to regulate the operation of said main valve, and means including a member associated with said mechanism and arranged to cooperate with said part to further regulate the operation of said main valve in addition to the regulation effected by said last-mentioned means. 50 60 65

11. In absorption refrigeration apparatus having a cooling element, a generator, and a burner for heating the generator, a control device comprising a gas pressure operated main valve for controlling flow of gas to the burner, means including an element responsive to pressure or temperature and auxiliary valve means operated 70 75

by said element to vary said gas pressure to effect operation of said main valve in a temperature or pressure range, said auxiliary valve means including a chamber having an outlet valve member, and means to increase or decrease the temperature or pressure range in which said

main valve is operated, said last-mentioned means including an adjustable member to determine the position of said element at which said outlet valve member closes.

SVEN W. E. ANDERSSON.
